UNITED STATES PATENT OFFICE

2,374,423

PIPE WRENCH

Frederick W. Davis, East Hartford, Conn.

Application December 30, 1942, Serial No. 470,573

1 Claim. (Cl. 81—103)

My invention relates to the class of devices above named, and an object of my invention, among others, is the provision in a wrench of means for effectually taking up lost motion between the fixed and movable jaws and to minimize the number of parts employed in mechanism for effecting this purpose.

One form of a wrench embodying my invention and in the construction and use of which the objects herein set out, as well as others, may be attained is illustrated in the accompanying drawing, in which—

Figure 1 is a side view of a pipe wrench embodying my invention.

Figure 2 is an edge view of the same.

Figure 3 is a perspective view of the device with the cover plate removed.

Figure 4 is a view in section on a plane denoted by the dotted line 4—4 of Fig. 1.

In the accompanying drawing the numeral 5 denotes the body or stock of my improved wrench, this comprising a bottom 6 and sides 7 preferably integrally formed together with a cover plate 8 removably attached to the body as by means of screws, as shown in Fig. 3. A pawl support 9 in the form of a dividing piece extends lengthwise within the body, about centrally thereof. This support also acts as a support for the cover 8 which is attached thereto as by means of screws. It forms recesses 10—11 for jaws 12—13, the jaw 12 being substantially stationary and formed at the end of a handle 14 while the jaw 13 is movable and comprises a shank 15.

These jaws are provided with gripping teeth 16—17 and the shank 15 is provided with ratchet teeth 18 on one edge which teeth are engaged by a pawl 19 pivotally mounted in a recess 20 in the upper edge of the pawl support, as shown in Fig. 3. This pawl has a pivot pin 21 which is mounted at one end in a hole in the support 9 and its opposite end serves as a pivot in the hole 22 in the cover plate 8. A finger piece 23 extends through an arcuate slot 24 in the cover plate as a means for operating the pawl to engage it with or disengage it from the ratchet teeth 18.

A guide pin 25 projects from the handle 14 in proximity to the jaw 12 thereon and a camming pin 26 extends from the handle 14 into a cam slot 27 in the cover plate 8, as shown in Fig. 3 of the drawing, the guide pin 25 extending into a guide slot 28 in the cover plate. The pins 25—26 are somewhat loose in their respective slots 28—27 so that a certain freedom of lateral movement is permitted for the jaw 12 and its handle 14, the recess 10 for these parts being also somewhat wider to permit this lateral movement.

In the operation of the device it will now be seen that the pawl 19 having been operated to permit the jaw 12 to loosely engage a piece of pipe 29, a lateral movement of the handle to turn the piece of pipe will bring the jaws 12 and 13 into tight engagement with the piece of pipe, the pawl 19 supporting the jaw 13 and the cam slot 27 acting on the camming pin 26 forcing the jaw 12 into tight engagement with the piece of pipe in opposition to the engagement of the jaw 13 therewith.

This camming action of the pin 26 in the slot 27 comprises a particular feature of my invention, as it permits a construction with a minimum number of parts and causes all looseness between the parts to be practically taken up as soon as pressure occasioned by force applied to the handle takes place.

In accordance with the provisions of the patent statutes I have described the principles of operation of my invention, together with the device which I consider to represent the best embodiment thereof; but I desire to have it understood that the device shown is only illustrative and that the invention may be carried out by other means and applied to uses other than those above set out.

I claim:

30 A pipe wrench comprising a substantially rectangular stock having parallel channels with thin side walls forming opposite sides of the stock and extending the entire length of the stock, and a thin dividing wall having a shallow cut-away portion in its upper edge spaced from the opposite ends thereof, a movable jaw member having a shank slidably mounted in one of said channels and having ratchet teeth formed on the inner edge thereof, a pawl pivotally mounted in said cut-away portion on the outer edge of said dividing wall to engage with said ratchet teeth, an active jaw having a shank mounted in the other of said channels, a cover removably secured to the outer side pieces of said channels and conforming to the boundaries of said stock, all of the parts consequently being confined within the width of said stock, a handle secured to the shank of said active jaw, a jaw formed on the end of the movable jaw member at right angles to the shank thereof to coact with said active jaw in grasping an article between them, a guide pin carried by the active jaw and extending through a guide slot in the cover plate, a cam pin on said active jaw extending through a cam slot in said cover plate and a finger piece on said pawl extending through a curved slot in said cover plate.

FREDERICK W. DAVIS,
